UNITED STATES PATENT OFFICE.

CASPER H. GRINGS, OF WATERLOO, IOWA.

HARNESS-SADDLE.

1,083,738.

Specification of Letters Patent.

Patented Jan. 6, 1914.

Application filed September 6, 1910. Serial No. 580,772.

To all whom it may concern:

Be it known that I, CASPER H. GRINGS, citizen of the United States, residing at Waterloo, in the county of Blackhawk and State 5 of Iowa, have invented certain new and useful Improvements in Harness-Saddles, of which the following is a specification.

My invention has relation to harness saddles and the leading thought is to provide 10 means for conveniently attaching and detaching the harness skirts in jockey plates whereby they will be rigidly held and adapted to be readily removed.

To this end my invention consists in a 15 jockey plate provided with means forming a part thereof and adapted to both clasp and pierce the skirt from opposite sides and hold the skirt of such grasp by the aid of the saddle terret.

20 The manner in which I accomplish these objects will be fully described in the following specification when taken in connection with the drawings accompanying the same and forming a part hereof.

25 Figure 1 is a perspective view of one side of a harness saddle with my invention attached. Fig. 2 is a longitudinal and vertical section of the pad and part of the yoke. Fig. 3 is a perspective view of the open 30 jockey plate, and Fig. 4 is a similar view of the cover, inverted, for the jockey plate.

Like characters of reference denote corresponding parts in each of the figures.

In the drawings, 2 designates the yoke, 4 35 the pad bottom, 5 the burr-piece or housing and 6 the terret. Upon the burr-piece 5 is secured the open jockey plate 8, which consists of a flat body made of metal turned up on the sides for a short distance at one end, 40 which sides form guards 12 to hold the skirt from any sidewise movement. These guards are connected together at the lower ends of their outer edges by a metal strap or loop 14. The open jockey plate 8 is provided with screw openings 15 and 16 through 45 which are inserted screws 18 and 20 by which the plate is secured to the burr-piece or housing and is also provided with an opening 22 through which the shank of the terret 50 6 passes. Near the screw 20 the plate is slightly bent or curved at 24 and near the bend is a rectangular opening 25 for locking and hinge purposes hereinafter to appear. Centrally of the plate and between the openings 15 and 22 is rigidly set a spud 26 which

extends upwardly to nearly the cover and preferably tapers from the bottom to the top, which spud is adapted to engage an opening in the skirt from the under side.

The cover plate 30 of the jockey consists 60 of a metal plate bent into a slight curve along the sides at 32 with a tongue 34 at one end and a locking hinge catch 35 at the other end, which is adapted to engage the yoke 2 in the opening 36 over the bar 38 and also to 65 engage the plate 8 in the opening 25 and serves not only to lock the cover 30 at that end onto the yoke, but also serves as a hinge to provide a flexible saddle. Near the outer end of the tongue 34 there is fixed a spud 37 70 similar to the spud 26 which is adapted to engage the skirt from the upper side at a short distance outward from the engagement of the skirt from the under side by the spud 26. 75

The skirt 40 is provided with two openings or holes 42 and 44. The opening 42 extends upwardly through or nearly through the skirt and preferably tapers from the bottom upwardly and is of such size as to 80 readily receive the spud 26. The opening 44 extends from the top downwardly through the skirt and is of sufficient size to easily receive the spud 37.

85 The manner of assembling and operating my device is substantially as follows: The open jockey plate 8 is secured to the burr-piece 5 by the screws 18 and 20 through the openings 15 and 16. Then the yoke 2 is placed upon the plate 8 with its opening 36 90 nearly registering with the opening 25 in the plate 8. The operator then inserts the catch 35 of the cover 30 through the opening 36 and through the opening 25 in the plate 8 with the point underneath the curve 95 portion 24 where it yieldingly holds the one end of the cover, and serves to hinge the yoke and jockey plate together. The skirt 40 is inserted under the loop 14 sufficiently far to allow the spud 26 to come into 100 engagement with the opening 42. Then the operator presses down the cover 30 and forces the spud 37 down through the opening 44 in the skirt until it rests upon the screw 18. The screw 45 of the terret 6 105 is passed through the opening 38 in the cover 30, through the opening 22 in the open jockey plate 8, through the burr-piece 5 and forces down the cover 30 upon the skirt and the spud 37 down through the skirt into 110

rigid engagement with the head of the screw 18, and at the same time forces up the plate 8 and with it the spud 26 up through the opening 42 in the skirt. In this manner it 5 will be seen that the skirt is rigidly held between the loop 14 and the plate 8 with the spud 37 piercing down through the skirt and the spud 26 piercing up through the skirt and holding the skirt wholly in the 10 grasp of the jockey plate from opposite sides and pierced by the spuds from opposite sides. It will also be seen that the spud 37 forced against the head of the screw 18 will prevent the screw from becoming 15 loose when in constant use. Also it will be seen that the pad will be flexible as the mode of holding the skirt does not interfere in any manner with the hinge. It will further be observed that if the terret should 20 break, as sometimes occurs, the skirt would not drop out or be liable to become disengaged, since the spud 26 projects underneath through or nearly through the skirt and the spud 37 from the top down through, 25 and further the skirt is held solely by the jockey plate, and the strain is divided equally on the spud in the open jockey plate and the spud in the cover or hinge clamping plate.

30 Having now described my invention what

I claim and desire to secure by Letters Patent is:—

In a device of the character described, a jockey-plate provided with a transverse hinge groove, and having a bent tongue at 35 one end and a transverse slot between the latter and the groove and a recess in its underside adjacent said slot, a loop at the opposite end of the jockey plate on the upper side thereof, flanges on opposite sides of the 40 upper face of the end adjacent the loop, a spud on the upper face of the plate between the loop and groove, the plate having a terret opening between the spud and groove, a yoke having a cross pin seated in said 45 groove, a cover plate having a terret opening and a bent tongue at one end and spud at the other end, said bent tongue passing through the slot in the jockey-plate and having its end located in said recess thereof, a 50 terret passing through the terret openings of the jockey and cover plates, and a skirt clamped between the cover and jockey plates and penetrated by said spuds.

In testimony whereof I affix my signature in presence of two witnesses.

CASPER H. GRINGS.
